MANUALLY-OPERATED MACHINES FOR ROLLING CIGARETTES

Edouard Roger Armelin, 70 Castlebar Road, Ealing,
London W. 5, England
Filed Dec. 7, 1959, Ser. No. 857,709
3 Claims. (Cl. 131—37)

This invention relates to manually operated machines for rolling cigarettes.

In the use of such machines a cigarette paper is drawn between an apron or a series of rollers and a column of tobacco confined by the apron or rollers so as to be wrapped about the column of tobacco, and moisture is applied to an adhesive on the trailing edge of the paper (or an adhesive is applied thereto), so as to cause adhesion of the trailing edge to the leading part of the paper that is already wrapped about the tobacco. Usually moisture is applied by licking the trailing edge of the paper. The object of the present invention is to provide a cigarette-rolling machine with self-contained means for causing adhesion of the trailing edge of the cigarette paper.

The present invention consists in the combination with a manually operated cigarette-rolling machine of a reservoir for liquid comprising porous material, the reservoir being so movably mounted upon the machine that the porous material may be contacted with the trailing edge of the cigarette paper, so as to apply liquid thereto, after the leading portion thereof has been wrapped about the tobacco and before the trailing edge is contacted with the leading portion.

The reservoir may comprise a thin generally rectangular casing having a narrow slot along one of its longer sides, the length of the slot being substantially equal to the length of the cigarette paper. The slot may be occupied by a porous wick, a felt or porous synthetic plastic material for example, which may project slightly beyond the lips bounding the slot, and may or may not completely fill the casing. The reservoir may conveniently be pivoted about an axis parallel with but remote from the slotted side to end frame members of the cigarette-rolling machine, so that, when the reservoir is rotated about its axis, the wick in its orbit sweeps the trailing edge of a cigarette paper already partly enwrapped about the tobacco in the machine.

The invention although not so restricted, is particularly applicable to two particular kinds of cigarette-rolling machine. In one of these kinds the rolling of the tobacco and the wrapping of the paper is effected by means of an apron loosely embracing a pair of rollers pivoted in end members of a frame, the cigarette paper entering between the nip of the rollers. In the other kind, the rolling is effected by a series of rollers, usually six, some of which, usually four, are pivoted in end members of a frame, and others of which, usually two, are similarly pivoted in end members of a cap or cover hinged to the frame, all the rollers being geared to one another, when the cover is closed, so as to revolve in the same direction and at the same peripheral speed.

For the better understanding of the invention, the application of it to cigarette-rolling machines of the two kinds referred to will now be described with reference to the accompanying drawings, in which:

FIG. 1 is a perspective view of a cigarette-rolling machine of the kind first referred to, provided with a reservoir according to the invention;

FIG. 2 is a transverse section of the machine shown in FIG. 1;

FIG. 3 is a section on the line III—III of FIG. 2;

FIG. 4 is a section of a machine of the second kind

2

referred to equipped with a reservoir according to the invention; and

FIG. 5 is a view in the direction of the arrow V of FIG. 4.

5 Referring now to FIGS. 1, 2 and 3, the machine to which the invention is here shown as applied, comprises a frame consisting of end members 1 and 2, located with respect to one another by means of spacing pillars. Two rollers 4 and 5 are mounted on trunnions in the end members 1 and 2 so as to be capable of being rotated about parallel axes. The trunnions of the roller 5, however, are movable in curved slots 6, so that the roller 5 may be approached closely towards the roller 4, as shown in FIG. 2, or may be retracted so that there is 10 a substantial space between the rollers 4 and 5.

The rollers 4 and 5 are embraced by a loose flexible apron 7.

In the normal use of a cigarette-rolling machine as so far described with reference to FIGS. 1, 2 and 3, first, 20 the rollers 4 and 5 are separated as much as possible by moving the roller 5 until its trunnions rest in the outer ends of the slots 6. Then shredded tobacco is inserted into the loop of the apron 7 formed between the rollers 4 and 5. The roller 5 is then approached towards the roller 4 to the position shown in FIG. 2, then the rollers are rotated causing the apron 7 to move and to roll the tobacco shreds into a column. Then the leading edge of a cigarette paper 8 is inserted between the parts of the apron resting respectively on the peripheries 25 of the rollers 4 and 5, which are then further rotated to draw the cigarette paper into the now constricted loop formed by the apron 7 to wrap it about the tobacco. At this stage the trailing edge of the cigarette paper, which is usually gummed, needs to be moistened, and 30 this has previously been done, as a rule by licking it.

40 The present invention provides self-contained means for causing adhesion of the trailing edge of the cigarette paper. As shown in FIGS. 1, 2 and 3, the end members 1 and 2 of the machine frame are extended somewhat perpendicularly to the axes of the rollers 4 and 5. Such extensions are preferably integral with the end members 1 and 2 but they may be separate parts attached to the end members. A thin, generally rectangular casing is pivoted between the extensions of the end members 1 and 2.

45 As shown, the end walls of the casing 9 are provided with trunnions 10 and 11 that are journaled in holes in the extensions of the frame members 1 and 2. The overall length of the casing 9 is slightly 50 less than the distance between the inner faces of the end members 1 and 2 so that the casing 9 and its trunnions may move axially relatively to the machine frame. A handle 12 is rigidly fixed to the trunnion 10 whereby the reservoir constituted by the rectangular casing 9 55 may be rotated.

The rectangular casing 9 is provided at one of its longer sides with a slot or opening 26 which is filled by liquid transfer means in the form of, in the case shown, a porous wick, a felt or porous synthetic plastic material 60 for example, which may project slightly beyond the lips 30 bounding the slot and may completely fill the casing, as shown, or may only partially fill the casing, leaving space for free liquid. The side of the casing opposite to the slot may be channeled as shown in FIG. 2 and may have 65 one or more small apertures by which liquid may conveniently be introduced to the reservoir so as to be absorbed by the wick 13.

70 As shown in FIGS. 1, 2 and 3, preferably closure means in the form of a cap or bar 15 extends between the end members 1 and 2, being, for example, attached to one of the facing pillars 3. This closure means is so located as

to be substantially tangent to the orbit of the wick 13, or equivalent, so that the wick, in its inoperative position, may abut against the closure means 15 whereby evaporation of liquid contained in the reservoir is retarded. In this case, means, such as a recess in one of the machine frame and reservoir or handle thereof, and a boss on the other are preferably provided to retain the reservoir in the position in which the wick 13 is covered by the closure means 15. Thus, as shown in FIGS. 1 and 3, a pin 16 projects from the handle 12 into a small hole in the end member 1. The trunnion 11 extends well beyond the end member 2 and is embraced by a compression spring 17 retained by a collar 18 or by a transverse pin, so as to urge the complete reservoir assembly to the left in FIG. 3 thus to cause engagement of the pin 16 with the hole in the end member 1.

In use, the reservoir constituted by the casing 9 and wick 13 is filled or saturated, usually with water, but, if desired, with scented liquid, or, in some case, with liquid gum. When the machine has been filled with tobacco and the cigarette paper 8 has been wound in to the position shown in FIG. 2 the handle 12 is rotated to cause the reservoir and wick to rotate in an anti-clockwise direction as indicated in FIG. 2, so that the wick wipes the trailing edge of the cigarette paper, while it is supported by the roller 4, and moistens it or applies adhesive to it. The handle 12 is then further rotated to restore the reservoir to the position shown in FIG. 2, whereupon the pin 16 is engaged with the hole in the end member 1 by the spring 17. Then the rollers 4 and 5 are further manually rotated to draw the cigarette paper 8 completely between them and wrap it around the column of tobacco, the moistened trailing edge adhering to the leading end of the paper.

Referring now to FIGS. 4 and 5 of the accompanying drawings, the machine to which the moistening device is applied is of the kind second referred to. The machine frame comprises a lower portion in the end members of which four fluted rollers 20 are journaled and an upper portion or cap 21 hinged to the lower portion 19, in which two fluted rollers 20 are journaled. The general arrangement, as shown in FIG. 4 is such that, when the cap 21 is closed upon the lower portion 19, the peripheries of the rollers are adjacent but do not actually touch. The several rollers are provided with individual external pinions which do not mate with one another but mesh with a gear wheel 23 mounted upon a spindle that is journaled in the end member and carries an operating handle in the form of a knurled disc 24.

In the application of the invention for this kind of manual cigarette rolling machine, the end members of the cap 21 are provided with extensions 25 upon which is mounted a reservoir assembly comprising a rectangular casing 9, wick 13, trunnions 10 and 11, handle 12, spring 17, collar 18, and pin 16, all precisely as described with reference to FIGS. 1, 2 and 3.

In operation, a column of shredded tobacco is assembled between the rollers 20, while the upper portion or cap 21 is opened. The cap 21 is then closed to the position shown in FIG. 4. The knurled disc 24 is then rotated manually to consolidate the tobacco and a cigarette paper 8 is introduced through a small gap that is present between the edges of the lower portion 19 and cap 21 of the machine frame so that it enters between the rollers 20 and, as rotation of the knurled disc 24 proceeds, is enwrapped about the column of tobacco. Just before the trailing edge of the cigarette paper 8 enters the small gap referred to and while it is supported by the edge of the cap 21, the handle 12 is rotated, so as to rotate the reservoir assembly anti-clockwise as shown in FIG. 4, so that the wick wipes and moistens the trailing edge of the cigarette paper 8. The handle 12 is then further manually rotated to restore the reservoir assembly in the po-

sition shown in FIGS. 4 and 5. Then the knurled disc 24 is further rotated until the cigarette paper 8 is completely wrapped about the tobacco and the trailing edge has adhered to the leading portion of the paper.

It will be appreciated that, while two particular constructions embodying the invention have been specifically described with reference to the accompanying drawings, many modifications may be made without departing from the scope of the invention.

10 What I claim is:

1. A manually-operated machine for rolling cigarettes comprising a frame having two end members, wrapping means comprising a plurality of rollers pivotally mounted in said end members about substantially parallel axes for wrapping a cigarette paper about a column of tobacco, a casing pivotally supported between said end members on an axis substantially parallel to, but separated from, the axes of said rollers, the said casing constituting a reservoir and having lips bounding a slot extending over its length parallel to and remote from its axis, porous material occupying said slot and projecting beyond said lips, the pivotal axis of the said reservoir being so located in relation to the axis of at least one of the said rollers that the orbit of the porous material is closely adjacent the said one of said rollers and, when the reservoir is rotated, the porous material sweeps the trailing edge, while supported by said one of the rollers, of a cigarette paper of which the leading portion is wrapped about tobacco contained within said wrapping means, a closure means attached to the said two end members and so located between the said two end members as to be substantially tangent to the orbit of the said porous material, so that the said porous material in its inoperative position is covered by the closure means.
- 15 20 25 30 35 40 45 50 55 60 65 70 75 80 85 90 95
2. A manually-operated machine for rolling cigarettes according to claim 1 and comprising detent means associated with said reservoir and said end members for releasably locking said reservoir relatively to said end members in the said inoperative position.
3. A manually-operable cigarette rolling machine comprising spaced end members, means for compacting a mass of tobacco shreds into a column and wrapping a cigarette paper about the column, a generally rectangular reservoir for liquid of length less than the distance between said end members, having a slot in one of its longer sides and two coaxial shaft means having portions respectively protruding from the opposite ends of said reservoir through said end members for pivotally supporting said reservoir between said end members, porous material in said slot, closure means extending between and fixed to said end members at such a distance from the axes of said shaft means as to cover said porous material when said reservoir is so positioned about the axis of said shaft means relatively to said frame that said slot is nearest said closure means, abutment means on the protruding portion of one of said shaft means, a compression spring disposed between said abutment means and the adjacent end member, a handle mounted on the protruding portion of the other of said shaft means, and co-operating male and female detent means on the opposed faces of said handle and the proximate end member, said detent means being urged into engagement with one another by said spring when the porous material in said slot is covered by said closure means.
